ELECTRICAL CABLE SPLICING MOLD

Manuel Filreis, Minneapolis, Minn., assignor to
Minnesota Mining & Manufacturing Company,
St. Paul, Minn.

Filed Mar. 26, 1974, Ser. No. 454,802

Term of patent 14 years

Int. Cl. D13—03

U.S. CL. D26—1 C

FIG. 1

FIG. 2

FIG. 3

FIG. 4

FIG. 5

FIG. 1 is a longitudinal elevation view showing one side of an electrical cable splicing mold embodying my new design, the opposite side constituting a mirror image thereof;

FIG. 2 is a top view thereof;

FIG. 3 is a bottom view thereof; and

FIGS. 4 and 5 are the end elevation views thereof.

I claim:

The design for an electrical cable splicing mold, as shown and described.
